[53] A POSTAL ACT

[37] **ABSTRACT**
An electronically tunable "YIG" sphere filter having plural sphere coupling in combination with input and output loop couplings for the first and last spheres, the structure providing performance characteristics not obtainable with ordinary loop coupling using a single or multiple gyromagnetic spheres. These characteristics include low insertion loss, wide tunable bandwidth, and wide constant instantaneous bandwidth, making the filter particularly suitable for superheterodyne electronic countermeasure receivers using multiple octave ranges.

ELECTRONICALLY TUNABLE MICROWAVE FILTER

This invention relates generally to electronically tunable microwave filters, and more particularly to one employing the characteristics of yttrium-iron-garnet (YIG) spheres. Devices of this general type are known in the art, and the invention lies in specific constructional details permitting improved performance.

BRIEF DESCRIPTION OF THE PRIOR ART

The characteristics of ferrimagnetic materials are extensively treated in "Microwave Ferrites and Ferrimagnetics" by Benjamin Lax and Kenneth H. Button, Copyright 1962, McGraw Hill Book Co., Inc., New York. Ferrimagnetic electronically tuned devices are disclosed in U.S. Pat. Nos. 3,426,297; 3,435,385; 3,517,351; 3,573,659 and 3,504,305, all of which are assigned to the assignee of the instant application.

BRIEF DESCRIPTION OF THE PRESENT INVENTION

Briefly stated, the invention contemplates the provision of a YIG sphere electronically tunable microwave filter including a plurality of spheres mutually positioned to permit sphere-to-sphere coupling via the external magnetic field set up in each sphere. This is accomplished by providing a cylindrical or square tube, and positioning the spheres in the tube. The input and output rf power is coupled via a loop to the first and last spheres. When the composite structure is immersed in a magnetic field H_{dc} and the spheres are resonated, the rf frequency f_o is coupled from the input loop to the output loop of the filter by the external magnetic field of one sphere to that of the other sphere, and so on through the array of spheres. The degree of coupling is dependent upon the size of the spheres and the spacing between them. The skirt selectivity of the filter is dependent upon the number of spheres in the array.

BRIEF DESCRIPTION OF THE DRAWING

In the drawing, the single FIGURE is a schematic view of an embodiment of the invention.

DETAILED DESCRIPTION OF THE DISCLOSED EMBODIMENT

In accordance with the invention, the device, generally indicated by reference character 10 comprises a cylindrical tube 11 of approximately 0.06 inches internal diameter and formed of non-magnetic metallic material. The tube extends for a length of approximately one inch between first and second ends 13 and 14, respectively. Supported on adjustable dielectric rods for tuning 15 and 16 are an input YIG sphere 17 and an output YIG sphere 18 which are grounded as known in the art.

Communicating with the spheres 17 and 18 are first and second coaxial transmission lines 19 and 20, the first line 19 having a terminal 22 supporting an input loop 23, the second line 20 having a terminal 24 supporting an output loop 25 coupling with the spheres 17 and 18, respectively, in well known manner.

Communicating with the tube 11 are first and second metal sleeves 26 and 27 supporting dielectric rods 28 and 29 respectively, the ends of the rods adjustably positioning the third and fourth YIG spheres 30 and 31 which are also grounded in coaxial position with respect to the ends of the tube 11, the interstitial distance

between the spheres 17, 18, 30 and 31 being substantially equal.

The required external magnetic field is provided between a north pole 32 and south pole 33 of an external magnet, again as known in the art.

THEORY OF OPERATION

In essence, the filter utilizes garnet spheres as resonators, and is tuned over a frequency range by means of the electromagnet. The resonant frequency (f_o) of the YIG spheres is determined by the field (H_{dc}) produced by the electromagnet.

The single-crystal YIG sphere contains unpaired electrons which yield magnetic moments as a result of their spins. When a dc field is applied to the sphere, the spin magnetic moments will precess about the axis of the applied H_{dc} field at a rate: f_o (MHz) = $2.8 H_{dc}$ (oersteds). The sense of precession is dependent upon the direction of the H_{dc} field.

In the present device, instead of providing input and output loops surrounding a single or multiple spheres, the input energy is coupled through the spheres via the external magnetic field set up in each sphere.

MEASURED PERFORMANCE DATA

A typical set of data taken of a K_u -band filter is given below.

	Freq. (GHz)	3 dB Bandwidth (MHz)	Insertion loss (dB)
30	12.4	68	3.2
	13.0	69	3.4
	13.5	70	3.2
	14.0	70	3.5
	14.5	70	3.7
	15.0	71	3.7
	15.5	72	3.5
35	16.0	72	3.4
	16.5	72	3.7
	17.0	73	3.3
	17.5	74	3.5
	18.0	74	3.2

An added advantage of the disclosed filter lies in the fact that the cylindrical (or square) tube structure behaves as a waveguide beyond cutoff and therefore affords greater isolation between input and output loops than the standard loop-coupled filter.

The relatively constant 3 dB bandwidth, and low insertion loss over the tested range may be observed from the above data.

I wish it to be understood that I do not consider the invention limited to the precise details of structure shown and set forth in this specification, for obvious modifications will occur to those skilled in the art to which the invention pertains.

I claim:

1. In an electronically tunable gyromagnetic sphere filter for coupling a pair of transmission lines, and including means for producing an external magnetic field, the improvement comprising: a hollow substantially uniform diameter tube, of non-magnetic metallic material, a plurality of gyromagnetic spheres in mutually spaced relation disposed within said tube along the principal axis thereof, input loop means surrounding one of said plurality of spheres, and connected to one of said transmission lines, and output loop means surrounding another of said plurality of spheres, and connected to the other of said transmission lines, whereby when said spheres are placed within an external magnetic field produced by said first mentioned means, said spheres will couple to each other via said external magnetic field.
